Primary Examiner — Susan Bennett Hattan*Assistant Examiner* — Marie Fast Horse(74) Attorney, Agent, or Firm — Venable, Campillo, Logan & Meaney P.C.(57) CLAIM

The ornamental design for a food box insert, as shown and described.

DESCRIPTION

FIG. 1 is a bottom perspective view of a food box insert;

FIG. 2 is a first end view thereof;

FIG. 3 is a second end view thereof;

FIG. 4 is a first side view thereof;

FIG. 5 is a second side view thereof;

FIG. 6 is a bottom view thereof;

FIG. 7 is a top view thereof; and,

FIG. 8 is a top perspective view of the insert in a non-claimed food box thereof.

The broken lines in the drawings depict environmental subject matter only and form no part of the claimed design.

1 Claim, 6 Drawing Sheets(56)
